LYMAN R. BLAKE.

Improvement in Channellers.

117,856.

Patented August 8, 1871.

UNITED STATES PATENT OFFICE.

LYMAN R. BLAKE, OF FORT WAYNE, INDIANA.

IMPROVEMENT IN MACHINES FOR CHANNELING THE SOLES OF BOOTS AND SHOES.

Specification forming part of Letters Patent No. 117,856, dated August 8, 1871.

To all whom it may concern:

Be it known that I, LYMAN R. BLAKE, of Fort Wayne, in Allen county, State of Indiana, have invented certain Improvements in Channelers; and I do hereby declare that the following, taken in connection with the drawing which accompanies and forms part of this specification, is a description of my invention sufficient to enable those skilled in the art to practice it.

My invention relates to certain improvements in channeling-machines, or that class of machines for skiving and channeling the edges of boots and shoes known as McKay channelers, such machines having two feed-wheels which support and feed the sole at the edge part thereof, a cutter or cutters which cut into or upon the surface of the sole at or near the edge, and a vertical guide-wall or face, which determines and controls the distance from the edge at which the channeler-knife shall enter. My present improvements relate to the method of adjustment of the mechanism to variably control the depth of the channel and its distance from the edge of the sole. My improvement consists in combining with a cutter-arm or lever made immovable longitudinally, having the upper wheel-shaft journaled in it, an edge-guide made adjustably movable toward and from the cutter or cutting-line, the shank of this edge-guide sliding in the front journal-stand, and not in the movable arm, and its attachments being entirely independent of the cutters or their means of attachment. The improvement also consists in journaling the front end of the upper feed-wheel shaft in a vertically-moving or vertically-adjustable block or journal-box, so that, by adjusting the block or box relatively to the journal-arm or lever, the wheel is raised or lowered relatively to the cutter or cutters to variably regulate the depth of cut.

The drawing represents a machine embodying the invention. A shows the machine in side elevation. B is a front view of it. C is a plan of the front end of the pivoted arm. D is a detail section on the line $\alpha\alpha$; E, a detail section on the line yy .

a denotes the base-plate; b and c, the front and rear journal-stands; d, the lower feed-wheel fixed on the end of the shaft e, which shaft is journaled in the two stands b c. z denotes the upper shaft journaled in the lever or arm f, which lever is hung on a pivot, g, in the rear journal-

stand, its front end passing through guide-cheeks h of the front stand, the feed-wheel i on the front end of the shaft being held down to the sole or toward the wheel d by the stress of a suitable spring, all in the usual manner. j denotes the edge-guide, just above the wheel d, and having a shank, k, which is supported and slides in the front stand b, the rear end of the shank having a lip, l, through which passes the shank of an adjusting-screw, m, the screw having flanges o, embracing the opposite sides of the lip, and the front or screw-threaded end working in a nut-thread in the stand. The shank of the edge-guide is supported and confined or guided by setting in a groove in the stand and by being covered by a top-plate, p. It will readily be seen that, by the screw m and these guiding-surfaces, the edge-guide is held in stationary position relatively to the tangential plane of the top of the lower feed-wheel, upon which wheel the sole is supported, and over which it is fed, and relatively to the cutting-plane of the cutter or cutters, and that, by moving the edge-guide forward or backward by means of the adjusting-screw, the distance of the channel from the edge of the sole may be readily varied, as circumstances may require, without movement of the cutters or of the movable arm. The rear end of the upper feed-wheel shaft is journaled in the rear end of the arm, but where the opposite end passes through the arm the arm is slotted vertically, so as to permit vertical movement of the shaft z; and in the front end of the arm is a block or bearing, q, in which the shaft is supported and rotates. This box q is confined between the arm and a cap-plate, r, and has at its top a flange, s, through a slot, t, in which passes the shank of an adjusting-screw, u, having collars v that embrace the flange s, the screw-threaded shank of this screw working in a nut-thread in the arm f. As the screw is turned in either direction the journal-block or box is raised or dropped, thereby raising or lowering the top-wheel i and variably regulating the depth of cut of the cutters, the depth of channel being determined by the extent of projection of the cutting-edges below the tangential plane of the bottom of the top-wheel. To one side of the adjustable journal-box is fastened, by screws w, the presser-foot x, that presses down the sole in the direct line of the cutters or directly abreast of the cutters, this foot thereby moving with the

journal-block and top wheel. It will thus be seen that neither the cutters nor the journal-arm or lever are disturbed by the provisions for adjustment of the depth of channel-regulating mechanism, or the distance of the channel from the edge-regulating mechanism.

I claim—

1. In combination with the lower feed-wheel and shaft journaled in stationary bearings, and the pivoted arm or lever *f* that carries the upper feed-wheel shaft, a stationary edge-guide, *j*, attached to the front stand, substantially as shown and described.

2. An edge-guide attached to the front stand

b, and made adjustable from said stand, substantially as shown and described.

3. In combination with the movable arm or lever and the cutters attached thereto, the adjustable journal-box *q* for raising and lowering the wheel *i*, substantially as described.

4. In combination with the wheel *i*, made adjustable, as described, the presser-foot *x*, attached to and moving with the adjustable journal-box.

LYMAN R. BLAKE.
